UNITED STATES PATENT OFFICE.

JOHN H. BALMER, OF MAPLEWOOD, NEW JERSEY.

DESIGN FOR A SHAVING-SET HOLDER.

Application filed September 23, 1924. Serial No. 10,883. Term of patent 3½ years.

To all whom it may concern:

Be it known that I, JOHN H. BALMER, a citizen of the United States of America, and resident of Maplewood, in the county of Essex and State of New Jersey, have invented a new, original, and ornamental Design for Shaving-Set Holder, of which the following is a specification.

Reference is had to the accompanying drawing in which the figure is a perspective view of a shaving set holder embodying a new design.

I claim:

The ornamental design for a shaving set holder as shown.

JOHN H. BALMER.
